UNITED STATES PATENT OFFICE.

FRANK WHITMAN, OF YPSILANTI, MICHIGAN, ASSIGNOR OF ONE-HALF TO
FRANK A. WORDEN, OF SAME PLACE.

OSCILLATING ENGINE.

SPECIFICATION forming part of Letters Patent No. 674,347, dated May 14, 1901.

Application filed June 11, 1900. Serial No. 19,917. (No model.)

To all whom it may concern:

Be it known that I, FRANK WHITMAN, a citizen of the United States, residing at Ypsilanti, in the county of Washtenaw and State of Michigan, have invented certain new and useful Improvements in Oscillating Engines, of which the following is a specification, reference being had therein to the accompanying drawings.

10 The invention consists in the peculiar construction and arrangement of the valves and operating mechanism therefor, and, further, in the peculiar construction, arrangement, and combination of parts, as more fully hereinafter described and claimed.

In the drawings, Figure 1 is a central longitudinal section through the cylinder of my engine, on the plane of the trunnions, on line *y y*, Fig. 2. Fig. 2 is a section at right angles to Fig. 1. Fig. 3 is a section on line *x x*, Fig. 1; and Figs. 4 and 5 are perspective views of some of the parts detached.

A is the cylinder of the engine, which is provided centrally on opposite sides thereof with trunnions B, journaled in the standards C, preferably in roller-bearings D therein. Through these opposite trunnions are formed, respectively, the steam and exhaust passages E and F, which connect with passages G and H, extending through the walls of the cylinder to opposite ends thereof.

I and J are the cylinder-heads, each of which is provided with a transversely-arranged cylindrical casing K, containing a rocker-valve L. The passages G and H are connected with the casings K by channels M and M', formed in the cylinder-heads, connecting with ports N and N' in the casings.

O represents ports leading from the casings into the cylinder.

The valves L are adapted to cover the ports O and N', and each is provided with a central channel P, adapted in one position of the valve to connect said ports O and N.

45 Q represents stems for rocking the valves, which pass out of the casings K through suitable packing-glands.

Around one of the trunnion-bearings D are secured the segmental racks R and R'. These 50 are preferably secured in position free to have

a limited rotary movement on the bearing by a ring S, which embraces the laterally-extending segmental flanges a on each of the racks. The racks are of such a length as to leave a space between their ends which will permit of 55 their being rocked through a limited angle.

T and T' are links pivotally connected to the racks R R', respectively, and connected at their opposite ends to a head or operating-handle U, which is adjustably secured upon 60 a stem V by means of a set-screw V'.

W represents gear-segments secured to the valve - stems Q and meshing with the segmental racks R and R'.

X is the piston in the cylinder, having a piston-rod X', which is directly connected to the crank, (not shown,) as usual in oscillating engines.

In operation steam is admitted through a suitable inlet-pipe having a swivel connection with the trunnion B into the passage E, from which it passes through the passage G, channels M, and ports N into the casings K at opposite ends of the cylinder. Here it is controlled by the valves L, which are so set 70 that when the racks R R' are in the position shown in full lines, Fig. 3, the engine will be driven in one direction, steam being admitted through the ports O when uncovered by the valve and exhausted through said ports, the 75 channels P, port N', channel M', and passages H and F. When the racks are moved into the position shown in dotted lines, Fig. 3, which may be accomplished by unfastening the set-screw V' and moving down the head 80 U on the stem V, the valves L will be rocked into a position to drive the engine in the opposite direction.

A point of advantage in my construction is that the clearances are reduced to a minimum, the valves L being located directly on the cylinder - heads, having only the small ports O between them and the cylinder-space.

A further advantage is obtained from the peculiar construction of reversing mechanism 95 which, while simple in construction, is easily operated and not liable to get out of order.

What I claim as my invention is—

1. In an oscillating engine, rock cut-off valves located on the opposite heads of the 100

cylinder, gear-segments on the stems of said valves and a stationary segmental rack with which said gear-segments mesh.

2. In an oscillating engine, the combination with the cylinder having a trunnion and a stationary bearing in which said trunnion is journaled, of rock cut-off valves at the opposite ends of said cylinder, gear-segments on the stem of said valves, segmental racks with which said gear-segments mesh journaled on said trunnion-bearings, and means for moving said rack-segments oppositely to reverse the valves.

3. In an oscillating engine, the combination with the cylinder having a trunnion, a stationary bearing in which said trunnion is

journaled and rock cut-off valves at opposite ends of said cylinder, having gear-segments on their stems, of the segmental racks R and R' having the laterally-extending flanges α , ²⁰ the ring S for securing said racks on the trunnion-bearing in mesh with said gear-segments, the links T and T' secured to said racks and the adjustable head U to which said links are connected substantially as and ²⁵ for the purpose described.

In testimony whereof I affix my signature in presence of two witnesses.

FRANK WHITMAN.
